UNITED STATES PATENT OFFICE.

FRANKLIN F. BRADLEY, OF CHICAGO, ILLINOIS, ASSIGNOR TO BRADLEY & VROOMAN COMPANY, OF CHICAGO, ILLINOIS, A CORPORATION OF ILLINOIS.

SQUEEZER.

1,094,974.

Specification of Letters Patent. Patented Apr. 28, 1914.

Application filed September 24, 1913. Serial No. 791,459.

To all whom it may concern:

Be it known that I, FRANKLIN F. BRADLEY, citizen of the United States, residing at Chicago, in the county of Cook and State of Illinois, have invented a certain new and useful Improvement in Squeezers, of which the following is a full, clear, concise, and exact description, reference being had to the accompanying drawings, forming a part of this specification.

10 this specification.
My invention relates to machines or implements for squeezing containers to effect the discharge of their contents and is of particular service for collapsing collapsible
15 tubes such, for example, as are employed for packaging tinting colors or oil colors, etc.

My invention has a number of characteristics among which are the provision of means for subjecting the discharge end of collapsible tubes to collapsing pressure exerted longitudinally of the tubes and the balance of the tubes to collapsing pressure exerted transversely of the tubes. By means of these two collapsing operations the entire tube contents are sure to be discharged since the comparatively thick and somewhat rigid conical shoulder walls at the discharge ends of the tubes are merely flattened from their dish form and are not buckled and bent so as to form material trapping spaces within the tubes. Furthermore, pressure exerted laterally of the tubes upon the conical shoulder walls at the discharge ends thereof would likely be followed by rupture of the tubes where the shoulder walls thereof join the complementary wall portions.

The machine of my invention is preferably stationarily supported and is desirably so positioned that the tubes or other containers to be collapsed will be held upright therein, but the invention is not to be limited to the stationary supporting of the machine nor to the position in which it holds the objects to be operated upon thereby.

I will explain my invention more fully by reference to the accompanying drawing showing the preferred embodiment thereof and in which drawing—

50 Figure 1 is a side elevation, partially in section, of a machine constructed in accordance with the invention, an altered position of some of the parts being indicated by dotted and dash lines; Fig. 2 is a front elevation
55 of the structure as it appears in full lines.

in Fig. 1; Fig. 3 is a sectional view on line 3 3 of Fig. 2 with parts, however, in altered positions; Fig. 4 is a sectional rear elevation of a part of the structure on line 4 4 of Fig. 1; Fig. 5 is a sectional plan view on line 5 5 of Fig. 1; and Fig. 6 is a longitudinal sectional view showing a tube in a partially collapsed condition, the lower end of the tube requiring further collapsing operation. 60

Like parts are indicated by similar characters of reference throughout the different figures.

The machine is preferably stationarily disposed, to which end it may be mounted upon a bracket 1 secured to a vertical support 2. An inverted uncapped collapsible tube 3, or other object to be operated upon, is supported upon a bracket 4 which in turn is anchored at its rear end to a vertical finger support 5 slidably supported in the bracket 1, to which finger support 5 the bracket 4 is adjustably secured by means of a set screw 6. The bracket 1, in addition to constituting a support for the machine, also carries a portion 7 at its front which constitutes a squeezing jaw. As this squeezing jaw is thus preferably made stationary, the collapsible tube is supported upon the bracket 4 by means of a holder 8 preferably in the form of a block or plate which is adapted freely to slide back and forth at right angles to the squeezing surface of the jaw 7 whereby the opposite wall portions of the tube, when collapsed, will be immediately adjacent the jaw 7 as indicated in Fig. 90

3. The squeezing jaw 9, which is complementary to the jaw 7, has a fixed pivot upon the bracket 1 at 10. This jaw 9 carries a cam element 11 which is adapted to be operated upon by a cam roller 12 journaled near the handle end of a hand lever 13 which is provided with a stationary pivotal mounting at 14 upon the bracket 1. A finger 15 projects from the cam element 11, the hand lever 13 in its idle position (indicated in Fig. 1) positioning the roller 12 to the rear of the vertical line passing through the pivot axis at 14 whereby the cam 11 and the jaw 9 fixed with respect thereto are held, when idle, in the position indicated by full lines in Fig. 1. When the tube is to be collapsed the slide block 8 is moved outwardly so that the uncollapsed tube may be vertically positioned against the jaw 7 as indi- 110

cated in Fig. 1. When the tube is thus positioned the hand lever 13 is drawn forward until it occupies the ultimate position indicated in Fig. 3, during which movement of 5 said hand lever the portion of the tube in engagement with the jaw 7 is collapsed, a result which is due to the fact that the center of the cam 11, when occupying the position indicated in Fig. 3, is sufficiently below 10 the pivot 14.

Collapsible tubes are usually provided with folds 3¹ to accommodate which the jaw 9 is provided with a recess 9¹. When the hand lever 13 has thus collapsed the part of 15 the tube 3 which has been pressed by the jaw 9 against the jaw 7, the part of the tube below the jaw 7 is now only partially collapsed as indicated in Fig. 6 and is adapted to be completely collapsed owing to the 20 parallel relation between the sliding holder 8 and the horizontal jaw element 16 (carried by the bracket 1) and the jaw element 17 (in fixed relation to the cam 11 and jaw 9) which has been brought to a horizontal position 25 when the lever 13 has been depressed to the position indicated in Fig. 3. The lower surfaces of the jaw elements 16 and 17 are included in the same horizontal plane when the parts occupy the position illustrated in 30 Fig. 3, the neck 18 of the partially collapsed tube then having its axis substantially in alignment with the middle of the space between the jaws 9 and 7, owing to the movement of the holder 8 in the general direction 35 in which the jaw 9 exerts collapsing pressure upon the tube. A hand lever 19 has fixed pivotal connection at 20 with the bracket 1 and is connected at its rear end by a link 21 with the slidably supported vertical finger 5, as indicated clearly in Fig. 3. When the hand lever 13 has effected adjustment of parts indicated in Fig. 3, the hand lever 19 is depressed whereupon the finger 5 is forcibly elevated to move the holder 8 40 forcibly upward against the composite jaw or squeezing member 16, 17 to collapse the portion of the tube which is shown in Fig. 6 to be but partially collapsed, the set of jaws or squeezing members 7, 9, and the set of 45 jaws or squeezing members 8, 16, 17 thus exerting collapsing pressures that are related

tively transverse, upon different portions of the tube. The holder 8 thus constitutes a squeezing jaw or member which is complementary to the composite jaw 16, 17. A 55 bracket 22 may be located below the tube 3 for the purpose of supporting a removable receptacle 23 beneath the tube that is being collapsed to receive the contents discharged from such tube. 60

By means of my invention the thicker conical end shoulder wall 24 of the collapsed tube is relieved of pressure exerted laterally of the tube and is subjected only to pressure exerted longitudinally of the tube to be 65 merely flattened, the machine thus insuring the discharge of all of the contents of the collapsed tube, the complete collapsing of the tube being unobstructed owing to the manner in which the pressure is applied to 70 the wall 24, the result of the collapsing operation being clearly indicated in Fig. 3.

While I have herein shown and particularly described the preferred embodiment of my invention I do not wish to be limited to 75 the precise details of construction shown as changes may readily be made without departing from the spirit of the invention.

Having thus described my invention I claim as new and desire to secure by Letters 80 Patent the following:—

A squeezer including a pair of squeezing members, one of which is movable toward the other; and a holder for the object to be squeezed in movable relation to both members, said holder being mounted freely to be moved by said movable member in the general direction in which squeezing pressure is being applied by such movable member, said holder being also movable toward said members transversely of the general direction in which pressure is applied to the object by said movable member whereby a portion of the object projecting beyond said members may be squeezed. 85 90 95

In witness whereof, I hereunto subscribe my name this 18th day of September A. D., 1913.

FRANKLIN F. BRADLEY.
